UNITED STATES PATENT OFFICE

HARRY C. CURRIER, OF MINNEAPOLIS, MINNESOTA

DESK TABLET

Application filed September 24, 1928. Serial No. 308,055.

This invention relates to desk tablets or paper holders, and the primary object is to provide an efficient, practical, and highly novel construction of holder of the class in which a roll of paper is supported and from which roll the paper is drawn or unwound as fast as it is used. A further object is to so construct the holder that a chamber will be formed to conveniently receive and retain notes or memoranda which the writer desires to preserve. A further object is to provide means for securing a piece of carbon paper to the device in such a manner that a roll of two strips of paper may be used, one strip running over and the other under the carbon, whereby an original and one carbon copy may be had of each writing. Further and more specific objects will be disclosed in the course of the following specification, reference being had to the accompanying drawing, wherein:

Fig. 1 is a perspective view of the device.

Fig. 2 is a sectional elevation taken centrally and longitudinally through the device.

Fig. 3 is a section of the paper support, as seen on the line 3—3 in Fig. 2.

Referring to the drawing more particularly and by reference characters 4 designates the bottom plate of a substantially rectangular base or housing having a rear wall 5, a front wall 6, and side walls 7, all of which walls are preferably integral with and bent up from the side and end edges of the plate 4. Near their rear ends the walls 7 are provided, at their upper edges, with slots 8. These slots, as shown, are preferably L-shaped, so that the spindle shaft 9 of the paper roll 10 will be firmly secured as against any tendency to dislodge it upwardly under the action of the pull on the paper which is taken off the bottom of the roll. The spindle 9 is further secured by having annular end slots, received by the notches, so that the spindle is virtually provided with heads to prevent endwise slipping of the spindle and also ties the side walls 7 firmly together.

As the paper strip leaves the roll 10 it is pulled over the upper edge of a partition or tongue 11, punched up from the plate 4. This partition defines the rear end of a chamber

or pocket A, and serves to hold this lower run of paper out of and above the chamber.

The writing support consists of a plate 12 having depending side flanges 13 that pivot at their upper ends, as at 14, to the side walls 7. At their lower ends the flanges 13 rotatably support a cross roller 15, over which the paper strip passes after leaving the tongue 11. It will be noted that the upper edge of the tongue 11 is substantially in line with the pivots 14, with a result that when the plate 12 is lifted up, to gain access to the chamber A, there will be no additional pull on or slack in the paper strip.

From the roller 15 the paper passes up through a slot 16, in the plate 12, and again down in a second slot 17 so as to pass under an angular portion 18 of the plate 12. The section 18 is supplemented by a similarly formed spring member 19 that is secured as by brazing or welding to the plate 12, as at 20. Thus the paper end is projected upwardly from and yieldingly retained between the members 18 and 19.

The members 18 and 19 are provided with registering finger holes 21, but these holes, it will be noted, do not reach the upper edges of the sections 18 and 19, although they are sufficiently large to permit a finger grip on the paper to pull it up sufficiently so that the projecting end may be then grasped and pulled. If the holes 21 were merely notches cut down into the members 18 and 19 this operation might be slightly facilitated, but in that event the upper edge of section 18 is practically useless as a cutting edge for tearing off used sections of the paper, as the open notch will invariably cause the paper to tear.

When the device is used merely as a memorandum pad a roll of only one strip of paper is used. When the device is used as an order or sales register, however, or for any other purpose where carbon copies are desired, a double strip roll is employed. In this event a piece of carbon paper 22 is inserted between the strips, over the writing surface of the plate 12, and is passed under the flanges 13 where it is secured by friction clips 23 pivotally secured to the flanges 13, as at 24.

When the exposed flat surface of the paper

- has been written on and it is desired to advance the paper so as to present a new and clean section, the operator pulls the paper end up, in the manner previously noted, and tears off the used portion against the upper 5 edge of the plate section 18. If he wishes to preserve the slip for future reference he lifts the plate 12, on its pivots 14, thus opening the chamber A where such slips may be deposited.
- 10 It is understood that suitable modifications may be made in the general design and structural details of the invention as herein shown, provided, however, that said modifications come within the spirit and scope of the appended claims.

Having now therefore fully shown and described my invention, what I claim to be new and desire to protect by Letters Patent is:

- 20 1. A device of the character described comprising a hollow frame adapted to support a roll of paper in one end thereof, a tiltable writing plate covering the other end of the frame and forming a chamber therewith, a 25 roller carried by the lower end of the plate over which paper is passed from the roll and to the upper surface of the plate.

2. A device of the character described comprising a hollow frame adapted to support 30 a roll of paper in one end thereof, a tiltable writing plate covering the other end of the frame and forming a chamber therewith, a roller at one end of the plate over which paper is passed from the roll and to the upper 35 surface of the plate, and means for holding the run of paper from the roll to the roller raised free from the chamber.

3. A device of the character described comprising a hollow frame adapted to support a roll of paper in one end thereof, a tiltable 40 writing plate covering the other end of the frame and forming a chamber therewith, a roller at one end of the plate over which paper is passed from the roll and to the upper 45 surface of the plate, and means for holding the run of paper from the roll to the roller raised comprising a tongue extending upwardly from the bottom of the frame.

4. A device of the character described comprising a frame having means for supporting 50 a roll of paper in the rear end thereof, an inclined plate positioned over the fore part of the frame and forming a chamber therewith, and a partition member arranged forwardly 55 of the roll to support paper from the roll and to form a rear wall for the chamber.

5. In a device of the character described, a paper roll support, a plate over which paper may be drawn longitudinally from the roll, 60 having depending side flanges and means for securing a transversely extending piece of carbon paper to the flanges of the plate.

6. In a device of the character described, a paper roll support, a plate over which paper 65 may be drawn longitudinally from the roll,

and means for securing a transversely extending piece of carbon paper to the sides of the plate, said means comprising a pair of releasable clips associated with lateral depending flange portions of the plate.

7. In a device of the character described, a base having a paper roll support at its rear, a writing plate pivotally secured to the base in advance of the support, said plate having a cutting strip, adjacent its pivoted end, under which the free end of the paper, from the roll, may be drawn, as used, said cutting strip having an opening, spaced from its cutting edge, through which the paper may be gripped and advanced.

In testimony whereof I affix my signature. 80
HARRY C. CURRIER.
